UNITED STATES PATENT OFFICE.

SEWARD D. HENDRICKS, OF BUFFALO, NEW YORK.

PROCESS OF CONSTRUCTING REINFORCED-CONCRETE BARGES, SHIPS, OR VESSELS.

1,209,159.

Specification of Letters Patent. Patented Dec. 19, 1916.

Application filed August 5, 1916. Serial No. 113,385.

To all whom it may concern:

Be it known that I, SEWARD D. HENDRICKS, a citizen of the United States, residing at Buffalo, Erie county, State of New York, have invented certain new and useful Improvements in the Process of Constructing Reinforced-Concrete Barges, Ships, or Vessels, of which the following is a specification.

10 My invention relates to barges, ships or vessels of any shape or size made from reinforced-concrete or other material formed by concretion.

15 It consists of a new and useful method or process of constructing barges, ships or vessels of this character.

In the accompanying drawing, which is illustrative and in no way limitative, Figure 1 is a side view of a reinforced-concrete 20 frame which is cast as a monolith. Fig. 2 is a side view of a reinforced-concrete side of a barge which side is cast as a monolith with the outside frame. Figs. 3 and 4 show some of the elements of the barge in spaced 25 relation before casting the bottom and ends. Fig. 5 shows the metal reinforcements 6 projecting from the bottom surfaces of the frames and sides to be suitably connected to the reinforcements of the bottom. Metal reinforcing in the frames and sides projects 30 from their bottom surface (6 in Fig. 5) and suitably connects and supports the reinforcing metal of the reinforced-concrete bottom to the frames and sides and other precast 35 members of the barge.

The method is to cast the frames, trusses, sides, sides with frames or trusses together, keelsons, girders, beams, bulkheads, partitions or other members of any desired shape 40 or size of reinforced-concrete as a monolith; after each monolith of concrete has set properly, to erect and suitably support them in their proper positions as is shown in Figs. 3 and 4. The bottom and ends are now cast 45 as a monolith of reinforced-concrete.

Having thus described my invention, I claim and desire to secure by Letters Patent,—

1. The method of constructing barges, ships or vessels of any shape or size of reinforced-concrete or other mass formed by concretion, which consists in casting frames, trusses, sides, sides with frames or trusses together, keelsons, girders, beams, bulkheads, partitions or other members of any 50 desired shape or size, of reinforced-concrete or other concretive material, as monoliths; and after each monolith of concrete has set, to erect and suitably support them in their proper positions and to cast the bottom and 55 ends as a monolith or in suitable sections.

2. The method of constructing barges, ships or other vessels of any shape or size of reinforced-concrete or other mass formed by concretion, which consists of casting 60 frames, trusses, sides, sides with frames or trusses together, keelsons, girders, beams, bulkheads, partitions or other members of any desired shape or size of reinforced-concrete or other concretious material as monoliths, having metal embedded and projecting 65 from the surface of the precast frames, trusses, sides, sides with frames or trusses together, keelsons, girders, beams, bulkheads, partitions or other members, which 70 projecting metal is suitably fastened to and supports the metal reinforcing of the bottom and ends; erecting and suitably supporting in their proper position these frames, trusses, sides, sides with frames or trusses 75 together, keelsons, girders, beams, bulkheads, partitions or other precast members after they have suitably set and cured; casting the bottom and ends as a monolith or in suitable sections.

SEWARD D. HENDRICKS.
